[57] CLAIM

An ornamental design for a one piece clipboard, as shown and described.

DESCRIPTION

FIG. 1 is a perspective view of a clipboard showing my new design;

FIG. 2 is a top plan view thereof;

FIG. 3 is a right side elevational view thereof, the left side being a mirror image thereof;

FIG. 4 is a front elevational view thereof; and,

FIG. 5 is a rear elevational view thereof.

The bottom plan view is unornamented and forms no part of the claimed design.
